UNITED STATES PATENT OFFICE.

FERDINAND SUCCESS OPPENHEIM, OF NEW YORK, N. Y.

CONTAINER.

Application filed December 17, 1924. Serial No. 756,461.

This invention relates to improvements in packing and shipping boxes or cases, and is particularly directed to a novel form of double walled container or carton constructed preferably of corrugated paper board or the like material for use in packing and shipping fragile articles or delicately constructed apparatus such as radio sets, meters, typewriters and the like.

10 An object of the invention is to provide a container of the character described which is of novel construction adapted to effectively protect and cushion the contents from sudden blows and contacts due to careless and rough handling during transportation, said construction including an improved form of top cushioning member which is adapted to brace the inner corner edges of the casing as will hereinafter appear.

15 A further object of the invention is to provide a container of the character described which is of simple construction, quick and easy to assemble, inexpensive to manufacture and efficient and practical to a high degree for the purposes described.

Other objects of this invention will in part be obvious and in part hereinafter pointed out.

Certain features herein shown and described are shown, described and claimed in my co-pending application Serial No. 736,805 filed September 10, 1924 and accordingly are not claimed herein.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a perspective view showing a packing and shipping box embodying the invention, parts of the box being broken away to show the interior;

Fig. 2 is a cross sectional view taken on line 2—2 in Fig. 1 showing the box closed and sealed with a radio set (shown in dotted lines) packed therein;

Fig. 3 is a perspective view of an improved side and end partition liner cushioning member;

Fig. 4 is a perspective view of a novel form of top cushioning member embodying the invention; and

Fig. 5 is a plan view of a blank from which the top cushioning member shown in Fig. 4 is formed.

Referring in detail to the drawing, 10 denotes an outer casing of a packing and shipping box or container embodying the invention which may have any desired shape or design and may be made of fibre board, card board, or the like material, but is preferably constructed of corrugated paper board, the cellular structure of which has been found to add greatly to the cushioning protection for the purposes described.

As seen in Fig. 1, the outer casing or shell 10 is of the usual collapsible construction to permit economical "knock down" shipment and comprises elongated side walls 11, end walls 12 and cover flaps 13, 14, 15, and 16, all preferably formed of a single sheet of material, cut, creased and folded to form a rectangular shaped shell 10, the cover flaps being adapted to fold inwardly to form the top and bottom walls for closing the casing. When the flaps are folded to their closed position they may be held by any suitable means as for example by a strip of adhesive tape 17.

Partition liners or cushioning members 18 are provided which are arranged against the side walls, end walls and the bottom. These liners may be substantially similar in construction and as seen most clearly in Fig. 1, each is preferably formed of a single sheet of corrugated paper board, cut, creased and folded to form a rectangular shaped body portion 19 having the opposite edge portions folded back from the normal front surface 19a of portion 19, and then infolded to form tubular sections 20. (See Fig. 3.)

The side walls 20 of the sections 20 serve to support the body portion 19 from the adjacent wall or bottom, the section 20 preferably being made relatively wide to extend a substantial distance inwardly of the edge of member 18 as shown in Figs. 1 and 2.

It will be understood that the shipping box is of suitable dimensions to enable packing the article or articles therein so as to substantially fill the space marked A in Fig. 2, and that the partition liners 18 are of proper design to completely cover the in-

terior sides and bottom of the casing 10 to the height of the contents, said liners 18 and contents preferably extending a substantial distance below the top of the casing for the purposes which will hereinafter appear.

Where the contents occupying space A (not shown) lies flush with the top edges of the liners 18, the body portion 19 may be arranged to abut the contents and where such contents (see Fig. 2) comprises a radio set having the usual levers and other like control means which project beyond its enclosing cabinet, a novel form of top cushioning member 22 may be provided which accommodates the said projecting parts and acts to support and space the set from the top cover of the casing.

As seen from Figs. 4 and 5, the top cushioning member 22 is preferably constructed of a single sheet of corrugated paper board cut to the shaped blank 22^a provided with crease liners 22^b and folded to have a rectangular shaped recessed body portion 23. All the edge portions of member 22 are folded to extend back and then infolded from the front surface 23^a of portion 23 to form tubular sections 24, the upstanding walls 24^a of said sections 24 serving to support and space the contents from the top of the casing.

The sections 24 are preferably made relatively wide so as to extend over into the packing space to provide a cushioning filler between the contents and the top of the casing 10 as shown in Fig. 2.

In the practice of the invention, the side and end partition liners 18 are first placed in position in casing 10 and are held in their respective places by means of the bottom liner 18 as is clearly shown in Figs. 1 and 2. Having arranged these liners in position with their body portions 19 spaced inwardly from the various walls of the casing, the radio set or other article to be packed is then lowered into place, the side wall of the set abutting against the walls of the liner 18 and being spaced thereby a substantial distance from the walls of the casing 10. With these parts in position, the top cushioning member 22 is inserted in the top opening of the casing with the recessed portions 23 thereof arranged to enclose the various projecting parts, and the section 24 abutting the panel of the set, the member 22 being dimensioned to the proper height to fill the space between the top of the set and the casing. The cover flaps are then folded into position and the casing sealed in any suitable manner as by means of a strip of adhesive tape 17.

Where the articles packed are relatively heavy, or if the shipping box is liable to be subjected to unusual rough handling during transportation, the liners 18 may be replaced by others constructed similarly to the

top cushioning member which being provided with sections 24 on all edge portions is relatively stronger.

From Figs. 1 and 2 it is apparent that casing 10 when fitted with liners 18 and 22 a top cushioning member 22 each having folded edge sections 20 and 24 respectively, is thus provided with substantial bracing means for the inner corner edges of said casing which also serve to cushion the contents from sudden blows and contacts if the box is carelessly and roughly handled during transportation.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A packing and shipping box comprising an outer casing, and a plurality of non-intersecting spacing partitions arranged to abut one another and to form the inner walls of the box, at least one of said partitions having edge portions thereof folded successively to extend down, outward, up and infolded from the normal front surface of said partition to form tubular sections, the side walls of said sections serving to support and space the partitions from the adjacent walls.

2. In a packing and shipping box, a partition liner made of a single piece of corrugated paper board creased and folded to form a rectangular shaped body portion having the opposite edge portions thereof folded successively to extend down, outward, up and infolded from the normal front surface of said liner to form tubular sections, the side walls of said sections serving to support and space the liner from an interior wall of the box.

3. In a packing and shipping box, a cushioning member made of a single piece of corrugated paper board creased and folded to form a rectangular shaped body portion having all the edge portions thereof folded to extend back and infolded from the normal front surface of said cushioning member to form tubular sections, the side walls of said sections serving to support and space the liner from an interior wall of the box.

4. A packing and shipping box comprising an outer casing and a plurality of non-intersecting spacing partitions arranged to

- abut one another and to form the inner walls of the box, each partition having edge portions thereof folded successively to extend down, outward, up and infolded from the normal front surface of said partition to form tubular sections, said sections serving as bracing means along the inner corner edges of the box and adapted to support and space the contents from the outer casing.
5. A packing and shipping box comprising an outer casing and a plurality of non-intersecting cushioning members arranged to abut one another and to form the inner walls of the box, at least one of said members having all the edge portions thereof folded to extend back and infolded from the normal front surface of said member to form tubular sections, said sections serving as bracing means which extend completely about the inner corner edges of the box and adapted to support and space the contents from the adjacent wall of the outer casing.
6. In a packing and shipping box, a cushioning liner made of a single piece of corrugated paper board, cut into a blank, creased and folded to have a middle rectangular shaped recessed portion adapted to accommodate projecting parts of the contents of the box, and tubular edge portions adapted to support and space the liner from the wall of the box and also to serve as bracing means for the inner corner edges of the casing, said tubular sections being folded successively to extend down, outward, up and infolded from the normal front surface of the liner.

In testimony whereof I affix my signature.

FERDINAND SUCCESS OPPENHEIM.
